(57) **CLAIM**

The ornamental design for a handgun projectile, as shown and described.

DESCRIPTION

FIG. 1 is an exploded top perspective view of a handgun projectile;

FIG. 2 is a bottom perspective view thereof;

FIG. 3 is an elevational view thereof;

FIG. 4 is a top plan view thereof;

FIG. 5 is a bottom plan view thereof;

FIG. 6 is a combined top perspective view of the handgun projectile;

FIG. 7 is a bottom perspective view thereof;

FIG. 8 is an elevational view thereof;

FIG. 9 is a top plan view thereof;

FIG. 10 is a bottom plan view thereof;

FIG. 11 is a sectional view;

FIG. 12 is a perspective view is an alternate embodiment;

FIG. 13 is an elevational view thereof; and,

FIG. 14 is a sectional view.

The broken line shown are included for the purpose of illustrating environment and forms no part of the claimed design.

1 Claim, 12 Drawing Sheets
